Primary Examiner — Jeffrey D Asch(74) *Attorney, Agent, or Firm* — Morgan, Lewis & Bockius LLP(57) **CLAIM**

The ornamental design for a cellular phone, as shown and described.

DESCRIPTION

FIG. 1 is a front, right side, perspective view of a cellular phone showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the drawings that are immediately adjacent to the shaded areas, and define an unshaded region, represent the bounds of the claim, while the broken lines within the boundaries are directed to environment. The broken lines and the unshaded regions form no part of the claimed design.
